UNITED STATES PATENT OFFICE.

JOSEPH CLIFFORD RUSSELL, OF PITTSBURGH, PENNSYLVANIA.

CARD INDEX.

1,423,029.

Specification of Letters Patent. Patented July 18, 1922.

Application filed October 12, 1920. Serial No. 416,377.

To all whom it may concern:

Be it known that I, JOSEPH C. RUSSELL, a citizen of the United States, and a resident of Pittsburgh, in the county of Allegheny and State of Pennsylvania, have invented certain new and useful Improvements in Card Indexes; and I do hereby declare the following to be a full, clear, and exact description of the invention, such as will enable others skilled in the art to which it appertains to make and use the same.

This invention relates to improvements in indexes and more particularly to a card index of the "visible" type in which the cards overlie each other in a holder or slide.

One object of my invention is to provide an index of the type specified, which shall be simple and substantial in construction, cheap to manufacture, and in which the continual bending of the cards to effect hinged connection thereof with their supporting means shall be avoided.

A further object is to so construct the index that the cards may be attached at their upper edges only to oscillatory supports which constitute hinge connections for the cards to the holder or slide frame.

A further object is to construct a visible card index in such manner that the cards shall be locked in oscillatory supports mounted in a holder or slide frame, and lie one upon another, and so that any card may be readily removed when necessary.

With these and other objects in view, the invention consists in certain novel features of construction and combinations of parts as hereinafter set forth and pointed out in the claims.

In the accompanying drawings; Figure 1 is a view of a "visible" card index illustrating an embodiment of my invention; Figure 2 is a transverse sectional view; Figure 3 is a longitudinal sectional view; Figure 4 is a perspective view of one of the oscillatory card supports and showing the manner of locking an edge portion of a card thereto, and Figure 5 is a view of one of the cards.

1 represents a frame or holder which may be constructed in the form of a slide to enter a suitable cabinet (not shown). The base 2 of the frame 1 may be recessed as at 3, whereby ledges 4 are formed near respective sides of the frame to receive respective end portions of card supports 5 more particularly hereinafter described. Enlargements 6, 6^a are located at or near respective sides of the

frame base 2 and upon these enlargements, members 7, 8 are disposed and overhang the ledges 4 so as to cooperate therewith in a manner to provide guideways for the end portions of the card supports. The member 7 at one side of the frame 1 may be fixed to or made integral with the enlargement 6^a, but the member 8 at the other side of the frame is hinged to the enlargement 6 so that it may be raised to facilitate the removal, insertion or rearrangement of the card supports and cards.

The oscillatory card supports are mounted freely side by side in the frame so that their end portions will be disposed in the guideways formed between the ledges 4 and the overhanging portions of the members 7, 8 and the cards connected with said supports and having tangential relation thereto lie freely, one upon another in such manner that the lower portions of the cards shall be exposed. In order that the cards near the lower end of the series shall lie flat, the base member 2 of the frame is made to form an inclined platform 9. To retain the several card supports in proper relation to each other and to prevent the escape of said supports, I provide a follower 10 slidingly mounted in the frame and held in position by friction springs 11 at one or both of its ends to engage the side walls of the interior of the frame, said side walls being formed by the enlargements 6 and 6^a. The follower 10 may be provided with a knob 12 to facilitate the manipulation thereof.

Each card support may consist of a cylindrical tube split longitudinally and having a flange 13 projecting inwardly from one of the edges, said flange being out of line with the axis of the tube and underlying the other edge, 14, of said tube. It will be observed that all portions of the wall of the tube (except the flange 13) are concentric with the axis of the tube. Each index card 15 is bent near its upper edge, whereby a flange 16 is formed and is disposed at an angle to the body of the card. The index card is inserted into the tubular support 5 from one end thereof so that its upper portion will be disposed between the edge 14 and the inwardly projecting flange 13 and so that the flange 16 of the card will project past the free edge of the flange 13 and be disposed at substantially right angles thereto,—the card bearing an approximately tangential relation to the tubular support.

It is evident that any pull which might be exerted on a card, in a direction at right angles to the tubular support, will cause the flange of the card to tend to mark a segment of a circle, but by reason of the disposition of said flange between the flange 13 and the wall of the tube, it will be impossible for the flange of the card to make any appreciable movement in the arc of a circle, and hence the card will effectually be locked to the tubular support. When a card is raised, there will be no hinge movement of any part of the card relatively to its support (which hinge movement would tend to weaken the connection of the card with its support) but the support itself will turn freely in its mounting in the frame, and all of the tubular card supports may be so freely mounted in the frame as to lie one against another.

In order to limit the movement of a card when the same is placed in a support and thus insure the proper position of the card between the ends of the support, the latter may be indented to provide a stop, as indicated at 17.

Having fully described my invention what I claim as new and desire to secure by Letters-Patent, is:—

30 1. In a card index, the combination with a frame, of a plurality of oscillatory card supports therein, each of said supports consisting of a split tube having an inwardly projecting flange at one edge, and a card 35 entering said split tube and disposed ap-

proximately tangentially thereto, said card having a flange disposed at approximately right angles to the flange of the tube within the latter.

2. In a card index, a card support consisting of a split tube having a circular cross section, one edge portion of the tube having an inwardly projecting flange out of line with centre of the tube, and a card entering the split tube and having a flange engaging the free edge of the flange in the tube.

3. In a card index, the combination of a card support consisting of a split tube provided at one of its edges with an inwardly projecting flange out of line with the centre of the tube, and a card entering the split tube and having a flange cooperating with the free edge of said inwardly projecting flange, and with the inner wall of the tube 55 to lock the card to the tube within the same.

4. In a card index, a card support consisting of a tube having a circular cross section and split from end to end, one edge of the split portion of the tube having an inwardly projecting flange, and a card stop closing a portion of the slit of the tube.

In testimony whereof, I have signed this specification in the presence of two subscribing witnesses.

JOSEPH CLIFFORD RUSSELL.
